UNITED STATES PATENT OFFICE.

ARTHUR O. FEILBACH, OF NORTH MILWAUKEE, WISCONSIN.

TOOL FOR LIFTING VALVE-SPRINGS.

1,328,228.

Specification of Letters Patent. Patented Jan. 13, 1920.

Application filed January 27, 1919. Serial No. 273,372.

To all whom it may concern:

Be it known that I, ARTHUR O. FEILBACH, a citizen of the United States, residing at North Milwaukee, in the county of Milwaukee and State of Wisconsin, have invented new and useful Improvements in Tools for Lifting Valve-Springs, of which the following is a specification.

This invention relates to a novel construction of tool, more particularly adapted for lifting automobile valve springs for the purpose of removing the pins or holding means for the valves.

The principal object of the invention is to provide means for holding the spring in raised position so both hands may be used for withdrawing the pin.

Another object of the invention is to make the device adjustable, so it may be used on different makes and sizes of automobiles.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like and corresponding parts throughout the several views, and in which:

Figure 1 is a view showing the tool in use.

Fig. 2 is a side view of the tool.

Fig. 3 is a cross section on line 3—3 of Fig. 1.

Fig. 4 is a top view.

Fig. 5 is a view showing another arrangement of the parts.

Fig. 6 is a sectional detail of the socketed member.

In these views, 1 indicates the head of the tool which is provided with an extension 2 having a plurality of screw threaded holes 3 in its outer part. 4 indicates a screw threaded rod having its lower end pointed and its upper end bent at right angle to provide a handle 5. This rod is to engage any one of the holes 3. A wing nut 6 is adapted to lock said rod in adjusted position in the holes. The head 1 is provided with a large bore 7 and a small bore 8, these bores passing through the head at right angles to the extension 2. The spring engaging member consists of a rod 9 passing

through the bore 7 and having its lower end bent at right angles. This bent end is provided with a hole not shown. The bent end is engaged by the socketed stem 11 of 60 the forked member 12. This stem is provided with a plurality of holes 13 to receive a pin 14 which passes through any one of the holes 13 into the hole in the bent end of the rod 9, whereby the fork member may be 65 adjusted on the rod 9. The forked end 12 is of circular formation and its upper face is recessed as at 15 to form a seat for the spring cup of the valve stem. A block 16 is adjustably secured to the rod 9 by means 70 of the bolt 17. This block forms a seat for a coil spring 18 carried by the rod 9 and having its other end bearing against the lower end of the head. In this way the spring tends to force the fork member and the extension 2 of the head apart. The block 16 carries a small rod 19, the upper 75 end of which engages the small bore 8 in the head and acts as a guide for the rod 9 and prevents turning movement of said rod. 80

20 indicates a hand lever having its lower end forked and pivoted by a pin 21 to the head. Beyond the pivotal point the forked ends extend at an angle to the handle and these ends are connected with the block 16 85 by the links 22.

It will thus be seen that when the handle is depressed into the position shown in Fig. 2, the block 16 and the rod 9 will be moved upwardly so as to compress the spring 18 90 and the parts will be held in this position due to the inclination of the forked ends of the handle.

As shown in Fig. 1, the device is placed in position on the motor with the pointed end of the rod 4 engaging the upper face of the valve and the fork 12 is placed under the spring cup on the valve stem. The handle 20 is then depressed so as to raise the rod 9 and this action will compress the valve 100 spring and raise the cup thereof above the pin in the stem. As the parts will be held in this position it will be seen that both hands of the mechanic may be used for withdrawing the pin.

As before stated, the tool may be adjusted to fit motors of different sizes by moving the forked member on the bent end of the rod 9 and by placing the rod 4 in the proper hole in the extension 2. This rod 2 is adjusted 110 in the hole, so as to bring the parts into proper position. The forked member may

be replaced by one of a different size to accommodate different sizes of motors.

In cases where the links 22 and the block 16 would come in contact with parts of the 5 motor and thus be prevented from moving, I place said block above the head with the links extending downwardly to the head, as shown in Fig. 5. In this case the spring 18 is omitted and the parts are returned to normal position by hand.

It is thought from the foregoing description that the advantages and novel features of my invention will be readily apparent.

I desire it to be understood that I may 15 make changes in the construction and in the combination and arrangement of the several parts, provided that such changes fall within the scope of the appended claims.

Having described the invention, what is 20 claimed is:

1. A tool of the class described comprising a head, an extension thereon, a screw threaded rod carried by said extension, a spring engaging member consisting of a rod 25 slidably carried by the head and having a bent end, means adjustable on said end for engaging the spring, a lever pivoted to the

head and means connecting said lever with said rod.

2. A tool of the class described, comprising 30 a head, an extension thereon, a screw threaded rod carried by said extension, a spring engaging member consisting of a rod slidably carried by the head and having a bent end, means on the said end for engaging the spring cup, a block connected with the last mentioned rod, a lever pivoted to the head and links connecting the same with the block.

3. A tool of the class described, comprising 35 a head, an extension thereon, having a plurality of screw threaded holes therein, a screw threaded rod adapted to engage any one of said holes, a spring engaging member consisting of a rod slidably carried by the 40 head and having a bent end, means carried by said end for engaging the spring cup, a block adjustably secured to last mentioned rod, a spring on said rod located between the said block and head, a hand lever pivoted to the head and links connecting said lever with the block.

In testimony whereof I affix my signature.
ARTHUR O. FEILBACH.
